(57) **CLAIM**

The ornamental design for a power driven carving knife, as shown and described.

DESCRIPTION

FIG. 1 is a front perspective view of a power driven carving knife showing our new design;

FIG. 2 is a rear perspective view thereof;

FIG. 3 is a top plan view thereof;

FIG. 4 is a right plan view thereof;

FIG. 5 is a lower plan view thereof;

FIG. 6 is a rear plan view thereof;

FIG. 7 is a front plan view thereof;

FIG. 8 is a second embodiment of the power driven carving knife;

FIG. 9 is a rear perspective view thereof;

FIG. 10 is a top plan view thereof;

FIG. 11 is a side plan view thereof;

FIG. 12 is a lower plan view thereof;

FIG. 13 is a rear plan view thereof; and,

FIG. 14 is a front plan view thereof.

The broken lines showing a knife blade in FIGS. 1-5 and 8-12 are for illustrative purposes only and forms no part of the claimed design.
